UNITED STATES PATENT OFFICE.

CARL MARCH, OF CHICAGO, ILLINOIS.

MATCH-BOX HOLDER.

Application filed September 8, 1926. Serial No. 134,316.

This invention relates to match box holders, and its primary object is to provide a holder designed to receive a box of matches commonly known as safety matches which are generally contained in a match carrier slidably mounted in a cover, and the said holder will not only prevent the box from being damaged, but includes means for automatically arranging the carrier to open position when it is desired to move a match therefrom.

A further object of the invention is to provide a holder for match boxes that is neat in appearance, strong and durable and contains few movable parts in its construction, with the result that it will be possessed with maximum life.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a perspective view of one form of the holder which forms the subject matter of the present invention.

Figure 2 is a front view showing the holder in open position.

Figure 3 is a perspective view of the body of the holder as shown in Figures 1 and 2 and also discloses a fragmentary part of the cover strip thereof.

Figure 4 is a fragmentary sectional view of parts of the body.

Figure 5 is a front elevation of a slightly modified form of the invention and showing the parts in closed position.

Figure 6 is a similar view but showing the parts in open position.

Figure 7 is a sectional view taken on line 7-7 of Figure 5.

Figure 8 is a perspective view of the body of the modified form.

Referring to the drawings in detail the letter A indicates a match box of the usual construction and which includes a match carrier and a cover therefor. The holder as shown in Figures 1 to 4 is provided with

a body 1 preferably formed from metal and is provided with a bottom 2, and end walls 3 and 4. The body also includes bridging strips 5 which have their ends bent at right angles as at 6 and said ends are secured to the end walls 3 and 4 so that the bridging strips will properly brace said walls as well as to provide guides for the match box as suggested in Figure 1 of the drawings.

The end wall 4 is longer than the end wall 3 and has its upper end bent in L-shape formation as at 7 in a manner to provide a space between the vertical portion of the L-shaped part and the wall 4 so as to accommodate one end of a flexible strip 8. The mentioned end of the strip 8 is fixed between the L-shaped portion and the wall 4 and thence covers the outer side of the wall, bottom 2, and the wall 3. The flexible strip 8 is secured adjacent the upper edge of the wall 3 by thread or other similar material 9 and is bent at intervals in its length beyond its connection with the wall 3 to provide a substantially U-shape formation to engage the opposed end walls of the cover A of the match box, and the top wall of the match carrier when said match box is disposed in said body with the carrier in closed position. Extending from the flexible strip 8 outwardly from adjacent the upper end of the wall 4, is a stud member 10 of a fastener and is adapted to receive the socketed member 11 which is fixed to the opposite end of the flexible strip as clearly shown in Figures 1 and 2 of the drawings.

Secured to the bottom 2 is one of the end convolutions of a pair of spaced parallel upstanding coil springs 11^a which are adapted to engage the bottom of the carrier for ejecting the same to open position as shown in Figure 2 when the socketed member 11 is released, but it will be obvious that the flexible member 8 retains the carrier in closed position and against the tension of the springs 11^a when the socketed member is operatively associated with the stud member 10. The flexible strip 8 is also secured to the wall 4 by thread as clearly shown in Figure 4 of the drawings.

In the modified form as shown in Figures 5 to 8 inclusive the body 1' of the match holder is somewhat similar to the body 1 of the form as shown in Figures 1 to 4 inclusive but it will be noted that the body not

only includes a bottom 2', and end walls 3' and 4', but front and rear walls 5' and 6' are provided. The match box A is disposed between the respective walls in the modified 5 form and a flexible covering 7' is also provided in this form and said covering has one end arranged about the upper edge of the wall 4' and secured thereto by thread and the like which passes through parallel openings 8'. The flexible covering also covers the bottom and end wall 3' and is secured to the end wall 3' by thread passing through openings 9', and the flexible covering thence is arranged in substantially U-shape formation 10 in the same manner as the covering 8 and is provided with a socketed member 10' adapted to be associated with the stud member 11' as suggested in Figure 5. Secured to the bottom 2' of the form just described is one end convolution of a substantially conical shape coil spring 12', while the uppermost and largest convolution of said spring 12' is secured to a follower plate 13' adapted to engage a carrier of a box of 15 matches as suggested in Figure 6 for elevating the same as shown in said figure when the flexible covering 7' is released.

From the above description and disclosure of the drawings, it will be obvious that the 20 match box holder which forms the subject matter of the present invention not only protects a box of matches from being damaged while being carried in the pocket of a user, but when the securing means for the 25 flexible cover is released, the coil springs will automatically elevate the match carrier to the positions as illustrated in Figures 2 and 6 and so that a match may be easily and readily removed from the carrier.

It is thought from the foregoing description 30 that the advantages and novel features of my invention will be readily apparent.

I desire it to be understood that I may 35 make changes in the construction and in the 40 combination and arrangement of the several parts, provided that such changes fall within the scope of the appended claims.

I claim:

1. A match box holder of the character described comprising a body, including end walls, one of said end walls being of greater length than the other, guide means between said end walls, a match box interposed between said end walls and said guide means, said match box including a cover and a 50 slideable match carrier therefor, a flexible strip covering the end walls and bottom with one end fixed to the upper portion of the long end wall, spring means between said bottom and the bottom of the carrier respectively for arranging said carrier to open position and said flexible strip being adapted to engage said carrier to retain the same against the tension of the spring in closed position, and fastening means for said 55 flexible strip which when unfastened allows the spring means to eject the carrier to open position.

2. A match box holder of the character described comprising a body which includes 60 a bottom and end walls, parallel strips also included in said body and having their ends disposed at right angles and connected to the end walls, an L-shaped portion formed on the upper end of one of said end walls, a 65 flexible strip having one end interposed between the vertical portion of the L-shaped portion and the last mentioned end wall respectively and covering the bottom and other end wall respectively, and thence extending 70 in substantially U-shape formation, said body being adapted to receive a match box which includes a carrier slidably mounted within a cover, spring means between the 75 bottom of the body and the bottom of the carrier respectively and being adapted to arrange the carrier to open position, and fastening means for said flexible strip for 80 securing the same over said carrier for retaining the latter closed and against the 85 tension of the spring means.

In testimony whereof I affix my signature.

CARL MARCH.
